[57] **CLAIM**

The ornamental design for a portable control system console or similar article, as shown and described.

DESCRIPTION

FIG. 1 is a front, perspective view of a portable control system console or similar article showing my new design;

FIG. 2 is a front elevational view thereof;

FIG. 3 is a bottom plan view thereof;

FIG. 4 is a rear elevational view thereof;

FIG. 5 is a left side elevational view thereof; and

FIG. 6 is a top plan view thereof.

The electrical connectors are shown in broken lines in FIG. 4 for illustrative purposes only.
